UNITED STATES PATENT OFFICE.

JOHN B. OWENS, OF ZANESVILLE, OHIO.

MEANS FOR COOLING TUNNEL-KILNS.

1,377,522.

Specification of Letters Patent. Patented May 10, 1921.

Application filed December 30, 1919. Serial No. 348,412.

To all whom it may concern:

Be it known that I, JOHN B. OWENS, a citizen of the United States, residing at Zanesville, in the county of Muskingum and 5 State of Ohio, have invented certain new and useful Improvements in Means for Cooling Tunnel-Kilns, of which the following is a specification.

In a tunnel kiln the continued intense 10 heat in the heat zone after days of operation has a tendency to affect the rails in the tunnel and the wheels of the cars which carry the goods or ware being burned, rendering it difficult to push the cars in the 15 kiln, as there is a tendency in the rails to buckle and the wheels to become distorted. These troubles sometimes render it necessary to close down the kiln until repairs are made, thus entailing expense and diminishing 20 production.

Overheating of the rails and wheels of the cars is caused by the brickwork on the inside of the heating zone becoming excessively hot and radiating this excessive heat 25 into the space below the car platforms.

One of the objects of my invention is to provide improved means for cooling the walls of the kiln and the brickwork under 30 the combustion chambers, for the purpose of minimizing the foregoing tendency.

With that end in view I provide air-circulating ducts, passages, pipes, or other conduits in the walls of the kiln opposite the space below the car platforms and, additionally thereto, other flues, ducts, pipes or 35 conduits in the brickwork under the combustion chambers. Embodiments of my improved cooling means are hereinafter described and appear in the accompanying 40 drawings but the showing thereof is to be considered as illustrative, and not restrictive, of the scope of the invention as modified arrangements could be resorted to.

The air circulating flues or conduits in 45 the walls of the tunnel kiln may extend from the exit or cooling end of the kiln to the stack, or, they may originate in the region of the combustion chambers or just beyond them toward the cooling zone and run to the 50 stack. The cooling flues or conduits in the brickwork under the combustion chambers may be open at both ends allowing the air to pass freely therethrough, or, these flues may be connected to the cooling flues or 55 conduits in the walls of the kiln. If de-

sired, there may be branch flues connecting with flues under the combustion chambers, such branch flues admitting air to the aforesaid flues. The arrangement of branch flues may be used whether the flues under 60 the combustion chambers are connected to the flues in the walls of the kiln or entirely separate therefrom. Cooling ducts pierce the tunnel walls below the car platforms.

In a tunnel kiln provided with the foregoing improvements, the combustion chambers may be provided with openings for the feeding of fuel gas or other fuel to the interior of said chambers. If these openings are in the sides of the chambers so that the 65 firing is at right angles to the length of the tunnel, partition walls may be provided between the fuel openings, said walls extending in general transverse relationship to the combustion chamber. These partitions will enable a maximum combustion and derivation of heat units to be obtained in the combustion chamber without damage to the goods on the cars when they arrive 70 opposite the combustion chamber. If preferred, the combustion chambers may be fired "longitudinally", that is, in the direction of their lengths, as set forth, for instance, in certain of my earlier applications, Serial Nos. 144,071; 237,166; 249,827; 80 251,294 and 277,718. Furthermore, baffles may be provided for the combustion chambers, or the chambers may be used without baffles, according to the requirements of the product being fired in the kiln. If baffles 85 are used, they may be arranged as disclosed in my earlier applications, instances of which are above recited. The partitions, instead of rising to the crown of the arch, may stop short thereof but still rise to meet 90 the baffle, if desired. These partitions may extend from the outer part of the arch to a serviceable distance from the car contents.

In the accompanying drawings, Figure 1 is a horizontal section of a tunnel kiln on line 1—1, Fig. 2, provided with 100 one embodiment of my invention;

Fig. 2 is a cross section on line 2—2, Fig. 1;

Fig. 3 is a detail horizontal section showing a modification where the air admission ends of the cooling ducts originate at the exit end of the burning zone;

Figs. 4, 5, 6, detail horizontal sections 105 showing modified arrangements of the cool- 110

ing ducts under the combustion chambers; and

Fig. 7, a section on line 7—7, Fig. 1.

While my improvements have particular reference to the "Owens" type of tunnel kiln, whether of the single or multiple zone class, and they are illustrated in connection with kilns such as set forth and claimed in earlier applications hereinbefore recited, 10 their use is not restricted to the Owens kiln as they may be embodied in other tunnel kilns.

In the present instance my improvements are shown embodied in an Owens kiln having a tunnel 1, stack 2, rails 3 on which the cars bearing the clay products or ware, travel. The entrance end of the kiln appears at 4 and the exit end at 5, the preheating zone is shown at 6, the multiple firing zone at 8, 8, 8, and the cooling zone at 7. The oppositely disposed combustion chambers 9 are arranged in pairs to provide the multiple firing zone set forth in my earlier applications, but there may be a greater number of zones than those shown. The oppositely arranged combustion chambers 9 are connected by a single arch 10 constituting the crown of the tunnel and the outer walls of the said combustion chambers. I 25 may, or may not, employ baffles such as shown at 11, when the present improvements are provided in a tunnel kiln. The floors or benches of the combustion chambers 9 appear at 12, and the openings 13 afford communication between the combustion chambers and the interior of the tunnel.

The combustion chambers may be fired "longitudinally" by the introduction of oil or fuel gas at 14, as proposed in my earlier 40 applications. If preferred, however, fuel gas may be introduced, with air in suitable volume, through ports or openings 15 extending from the sides of the arch 10 through said arch to deliver the fuel gas 45 transversely of the combustion chambers 9. When this latter delivery of the fuel gas is used, I preferably subdivide the chambers 9 into a plurality of compartments 16 by providing partitions 17. The fuel gas may 50 be delivered upwardly through the floors or benches 12 as shown at 18, if desired. This delivery may be resorted to in connection with the delivery of the fuel gas through the openings 15, or, in lieu thereof. The delivery 55 of the fuel gas into compartments within the combustion chambers 9 insures better combustion and the delivery of the heat and products of combustion to the clay products or ware 19 in a manner which will 60 minimize damage thereto.

The platforms 20 of the cars having the wheels 21 which run on the rails 3, lie substantially in line with the floors or benches 12.

65 The arch 10, in each instance, serves the

same purposes as explained in connection with certain of my aforesaid applications.

As previously explained, the excessive heat developed in a tunnel kiln may, after a certain period of operation, bring the 70 walls of the tunnel 1 to such a temperature by heat radiated therefrom into the space 22 below the car platform 20 that the rails 3 will buckle and the wheels 21 become distorted, rendering it difficult to push the cars 75 through the kiln and necessitating closing down of the kiln until repairs may be made. This tendency is observable in the firing or 80 heat zone 8, 8, 8, where the temperature is highest. For the purpose of cooling the 80 walls of the tunnel 1 and to overcome the excessive temperature brought about in the space 22 by radiation from said walls, I 85 provide flues, ducts, conduits, or the like, 23, running lengthwise in said walls. These 85 flues, ducts, or conduits may extend from the extreme exit end 5 of the kiln to the stack 2, there being a suitable cross flue 24 to conduct the air from the flue in the wall farthest from said stack, to said stack. 90 The flues 23 are open to the outer air at 25. This construction is shown in Figs. 1, 2, 4, 5, 6. If preferred, the flues 23 may originate at the exit end of the firing or heat zone 8 and open out laterally through the walls 1 95 as at 26, Fig. 3, thence running to the stack 2.

Extending through the brickwork under the floors 12 are other flues, ducts or conduits 27 for the purpose of providing additional free circulation of air through said 100 brickwork to cool the same and reduce the temperature of the walls where they face the heat zone 8, as the temperature in the heat zone is the highest at this point of any part of the length of the kiln. As shown in Figs. 105 1, 4, 5, the flues, ducts or conduits 27 open out through the end faces of the brickwork.

These flues or ducts 27 may be cross-connected with the flues 23 by branches 28. Additional air supply may be obtained by providing a number of branch air admission or inlet ducts or flues 29 leading from the side of each arch to the flues 27. This latter construction may be used whether flues 27 are connected to the flues 23, or are separate 115 therefrom. This construction is shown in Figs. 2, 4, 5, 6.

Other arrangements and modifications may be resorted to in accomplishing the cooling of the walls of the tunnel 1 and the 120 brickwork of the benches 12 under the combustion chambers 9, and I do not limit myself to the precise embodiments of the cooling means herein described and which are shown in the drawings.

To assist in maintaining suitably low temperature in the space 22 there may be provided ports, ducts, or conduits 30 which pierce the lower parts of the walls of the tunnel and communicate with the space 22, 130

allowing outer air to flow directly into said space 22. While I have shown these ports 30 at certain points of the length of the tunnel, I do not limit myself to any particular points for the location.

Referring to Fig. 7, to take off the air from the space 22 below the car platforms, there is provided the draft outlets 31, 31, extending through the tunnel walls and 10 communicating with said space 22 and the down-flues 32. The down flues 32 communicate with the cross flue 24 which leads to stack 2.

If preferred, the draft ports 33 which 15 take off the heat from the tunnel above the car platforms, may be extended downwardly as at 34 (shown by dotted lines) to communicate with space 22 and thus serve as a substitute for ports 31.

20 What I claim is:—

1. A tunnel kiln provided with air circulating flues or ducts extending lengthwise within its walls opposite the space below the platform of the ware conveying means.

25 2. A tunnel kiln provided with air circulating flues or ducts extending lengthwise within its walls opposite the space below the platform of the ware conveying means along the sides of the firing or burning zone.

30 3. A tunnel kiln provided with air flues or ducts extending lengthwise within its walls and located opposite the space below the platform of the ware conveying means said flues or ducts being connected to the stack or other draft inducing means for the kiln.

40 4. A tunnel kiln having oppositely disposed combustion chambers provided with floors or benches, and cooling flues or ducts in said benches located opposite the space below the platforms of the ware conveying means.

45 5. A tunnel kiln having oppositely disposed combustion chambers provided with floors or benches, and cooling flues or ducts in said benches located opposite the space below the platforms of the ware conveying means, said air flues or ducts extending from 50 one end of the bench to the other end thereof for the free circulation of air therethrough.

55 6. A tunnel kiln having oppositely disposed combustion chambers provided with floors or benches, and cooling flues or ducts in said benches located opposite the space below the platforms of the ware conveying means, said air flues or ducts extending in 60 the direction of the length of the benches, and branch flues or ducts extending inwardly from the sides of the benches and connected to the air flues or ducts aforesaid.

7. A tunnel kiln having cooling air flues

or ducts located in its walls opposite the space below the platforms of the ware conveying means and extending lengthwise of the tunnel opposite the burning or firing zone, said kiln having combustion chambers provided with floors or benches, and additional cooling air flues or ducts located in 65 the benches opposite the space below the platforms of the ware conveying means.

8. In a tunnel kiln having a tunnel through which the ware may be conveyed and which is provided with a combustion 70 chamber at its side said chamber being in communication with the interior of the tunnel, a plurality of ports or openings for the admission of fuel gas into said combustion chamber in general crosswise relation 75 thereto.

9. In a tunnel kiln provided with a combustion chamber at its side which is in communication with the interior of the tunnel, a plurality of ports or openings for the admission of fuel gas in general crosswise relation to said combustion chamber, said combustion chamber being provided with partitions subdividing it into a plurality of compartments with which said ports or 80 openings respectively communicate whereby combustion may be carried on in the respective compartments.

10. In a tunnel kiln, a combustion chamber located at the side thereof which is provided with a plurality of compartments, each opening into the interior of the tunnel, and means for carrying on combustion in the several compartments.

11. A tunnel kiln having air draft-inducing means acting on the entire length of the tunnel, means for taking off the draft which is subject to said draft-inducing means, and supply openings extending through its walls and admitting air into the space in which 100 the running gear of the cars travel.

12. A tunnel kiln having air supply openings extending through its walls for admitting outer air to the lower section of the tunnel at various points of its length, and a stack communicating with both the upper and lower parts of said tunnel.

13. A tunnel kiln having a preheating zone, a firing zone, and a cooling zone, means for inducing draft lengthwise within the tunnel, and flues leading from the space below the cars to said draft-inducing means.

14. A tunnel kiln having a preheating zone, a firing zone, and a cooling zone, means for inducing draft lengthwise within the tunnel, and flues leading from the spaces above and below the cars to said draft-inducing means.

In testimony whereof I affix my signature.

JOHN B. OWENS.
